TUBE-SWAGING MACHINE

Application filed January 2, 1926. Serial No. 78,885.

Our invention aims to provide a swaging machine in which the ends of the tubes may be expeditiously and economically swaged, the machine being of that type in which a quantity of tubes may be placed and automatically operated upon without the attention of an attendant, other than that of loading the machine from time to time and removing the swaged tube.

Our machine will be hereinafter specifically described and then claimed, and reference will now be had to the drawings, wherein

Figure 1 is a side elevation of the machine with the central portion thereof broken away; Fig. 2 is a horizontal sectional view of the machine;

Fig. 3 is a cross sectional view of the machine;

Fig. 4 is a cross sectional view of a portion of the machine showing one of the cam members;

Fig. 5 is a longitudinal sectional view of one of the swaging instrumentalities relative to the end of the tube;

Fig. 6 is a similar view showing the swaging instrumentality actuated to shape the end of the tube;

Fig. 7 is a perspective view of a tube end before being swaged, and

Fig. 8 is a similar view of the tube end after being swaged.

Our invention comprises a suitable base 1 provided with end frames 2 and mounted on said end frames are bearings 3 for a longitudinally disposed driven shaft 4 having one end thereof provided with a pulley 5 by which the shaft may be driven. The pulley 5 is an example of various kinds of power devices that will facilitate rotation of the shaft 4.

Mounted on the central portion of the shaft 4 is a tube carrier, composed of a plurality of spaced cylindrical members or drums 6 having the peripheries thereof provided with longitudinal tangentially disposed grooves or pockets 7 adapted to automatically pick up or receive tubes 8 from a tube magazine 9a having an inclined bottom wall 10a which causes the tubes 8 to feed towards and against the rotary tube carrier.

The tube carrying members 6 may be spaced apart to cooperate in supporting tubes of various lengths so that the ends of the tubes will project from the endmost members.

Mounted on the shaft 4, adjacent the ends of the rotary tube carrier, are holders 9 for circumferentially arranged swaging instrumentalities adapted to operate upon the projecting ends of the tubes 8. The holders 9 are identical in construction and one need only be described with special reference to Figs. 5 and 6.

Each swaging instrumentality comprises a plunger 10 having one end thereof provided with a head 11 abutting one end of the holder 9 and retained in engagement therewith by the expansive force of a spring 12 encircling the plunger 10 between the holder and a spring abutment 13 mounted on the plunger against a stop pin 14 carried by the plunger.

The plunger 11 has a seat 15 for a swaging die 16 having an end configuration 17 to receive the end of a tube 8. The die 16 is tubular and contains a stripper 18 held stationary by a screw 19 of the holder 9, said screw extending through a slot 20 in the plunger 10. The plunger 10 has a bore 21 to receive the stripper and while this stripper is held stationary by the holder 9 the plunger 10 may be actuated to swage, contract or reduce the end of the tube 8, as at 22. After the plunger has been reciprocated to swage the tube and is released by its reciprocating means the expansive force of the spring 12 retracts the plunger, and in considering the swaging operations as being simultaneously performed on the ends of the tube, it is obvious that the tube cannot shift in the rotary carrier nor conveniently buckle therein due to endwise pressure. When the springs 12 retract the plungers 10, the swaging dies 16 are pulled off of the ends of the tube, but should one or both of said dies tend to skid the strippers 18 will prevent the tube from following either die as it is retracted.

Fixed to the end bearings 3 and surrounding the shaft 4 are the hub portions 23 of semi-cylindrical stationary members 24 hav-

ing the side faces thereof which confront the holders 9 provided with cam members 25 against which the plungers 10 impinge and are reciprocated as the holders 9 are rotated 5 in synchronism with the rotary tube carrier.

The stationary members 24 are connected by a longitudinally disposed support 26 and the bearings 3 are provided with brackets 27 10 for a longitudinally disposed support 28. The supports 26 and 28 cooperate in supporting the tube magazine 9a which has its end walls cut away to provide clearance for the rotary tube carrier and thus permit of the 15 bottom wall 10a extending in proximity to the rotary carrier.

On the base 1, below the rotary tube carrier, may be placed a tube container 29 to receive tubes from the grooves or pockets 7 20 of the rotary carrier.

In operation, the shaft 4 is driven in a counter clockwise direction viewing Fig. 3, and tubes 8 are picked up from the magazine 9a and carried around towards the container 29. As the tubes leave the magazine 9a the plungers 10 encounter the upper ends of the cam members 25, and the rise of each cam member is gradual so that the plungers will be gradually actuated to force the dies 16 on 25 the protruding ends of the tubes 8. The swaging operations are carried on until the lower ends of the cam members 25 are reached, where the plungers 10 are abruptly released by said cam members; there being somewhat 30 of a snap action which will withdraw the dies from off of the ends of the tubes. As the dies release the tubes at the lower ends 35 of the cam members the tubes are then free to drop by gravity out of the grooves or pockets 7 into the container 29.

Our invention may be advantageously used for producing tubes or conduits adapted to form part of automobile radiators and other cooling devices, wherein the ends of the tubes 45 are mounted in headers, tank walls, fins and heat disseminating elements. Ordinarily, the tubes are cut to desired length and in cutting or sawing the tubes burrs or rough edges often remain. Sometimes the wall of a tube 50 is distorted by the sawing or cutting operation, and the burrs, irregularities and wall distortions often destroy the metallic contact of the tube with an adjoining member. In the manufacture of radiators it is essential 55 that there be a positive metallic contact of tubes, fins and the like for radiation purposes, and in designing our swaging machine we have aimed to eliminate burrs, irregularities 60 and wall distortions so that there may be a positive and reliable fitting together of tubes, fins and the like. The swaging action, which has been somewhat exaggerated in the drawings, is adapted to shear off burrs or depress the same, smooth out irregularities, and 65

properly shape any distorted tube wall so that the end of the tube is perfect for mounting in the core of a radiator.

It is thought that the operation and utility of our swaging machine will be apparent without further description, and while in the drawings there is illustrated a preferred embodiment of our invention, it is to be understood that the structural elements are susceptible to such variations and modifications as fall within the scope of the appended claims.

What we claim is:

1. In a tube swaging machine, a driven rotary tube carrier having longitudinal grooves adapted to support a plurality of tubes horizontally, a tube magazine adapted to contain tubes horizontally and receiving the groove portion of said carrier, a holder driven in synchronism with said carrier, swaging instrumentalities carried by said holder and adapted for swaging the ends of tubes carried by said carrier, and stationary means engaged by said swaging instrumentalities adapted to actuate said swaging instrumentalities for swaging purposes. 80

2. In a tube swaging machine, a driven rotary tube carrier, a holder driven in synchronism with said carrier, swaging instrumentalities carried by said holder and adapted for swaging the ends of tubes carried by said tube carrier, stationary means engaged by said swaging instrumentalities adapted to actuate said swaging instrumentalities for swaging purposes, each swaging instrumentality including a plunger, a swaging head carried by said plunger, and a stripper in 95 said plunger. 100

3. A tube swaging machine comprising tube carrying means from which the ends of the tubes project to be swaged, two sets of swaging instrumentalities adjacent said tube carrying means and adapted to simultaneously operate upon the ends of a tube, stationary means engageable by said swaging instrumentalities to cause a gradual actuation of said swaging instrumentalities, and supporting means for said tube carrying means and said swaging instrumentalities so that said tube carrying means and said swaging instrumentalities may be moved in unison relative to said stationary means, the said swaging instrumentalities including reciprocal swaging heads with stationary strippers therein. 105 110

4. A tube swaging machine as called for in claim 3 further characterized by means for abruptly withdrawing the swaging instrumentalities from said tube ends. 125

5. A tube swaging machine as called for in claim 3, wherein said stationary means includes cam members by which said swaging instrumentalities are gradually placed in operation and quickly released. 130

6. A tube swaging machine as called for in
claim 3, wherein said supporting means in-
cludes a driven shaft with said tube carrying
means and said swaging instrumentalities
mounted thereon.

5 In testimony whereof we affix our signa-
tures.

HARRY A. HIGGINS.
